CONNECTOR

Robert R. Steinke, West Somerville, Mass., assignor, by mesne assignments, to the United States of America as represented by the Secretary of War

Application November 4, 1944, Serial No. 561,989

4 Claims. (Cl. 173—328)

1

The present invention relates to a high voltage cable connector or detachable coupling for use in circuits requiring cables to conduct high voltage pulses. It is more particularly directed toward a connector for use with coaxial type cables, such as are used in high voltage modulator circuits, for example, those where a high voltage cable must be used to connect a pulse-forming network to a rotary spark gap which is usually attached to the shaft of a driving motor. In circuits required to conduct high voltage pulses, it is necessary to provide a connector or coupling unit for the cable which will not fail due to corona or sparkover.

The principal purpose of the present invention is to provide a readily detachable plug connector or coupling which will at the same time be effective to terminate the cable.

Another object of the invention is to provide a connection which will have good electrical conductivity at high voltage and which is not subject to failure due to flash over or corona.

Other features and advantages of the invention will become readily apparent as the description proceeds, reference being had to the accompanying drawings wherein a preferred form of the invention is shown. It is to be understood, however, that the drawing and description are illustrative only and are not to be taken as limiting the invention to the specific details set forth.

In the drawings:

Fig. 1 is a sectional view on a diametrical plane through the plug element of the present invention showing a cable end attached thereto;

Figure 1A is a detail of the parts coupling the plug and socket shown in Figures 1 and 2;

Fig. 2 is a sectional view on a diametrical plane through a preferred embodiment of the socket element of the present invention; and

Fig. 3 is an expanded, perspective view of one form of a cable end showing the construction thereof and indicating the manner in which several members of the plug element are applied to the cable end.

With reference to Fig. 1, the plug element comprises a body portion shaped as a hollow cylinder or cylindrical shell 10 of steel, brass, or other suitable metal, the rear end (to the left in Fig. 1) of which is externally threaded at 11 to receive an internally threaded cylindrical clamping nut 12. Clamping nut 12 has an inwardly disposed flange 13 adapted to fit over and abut a flange portion 14 extending outwardly substantially at right angles from the inner or forward end of a cylindrically shaped cable bushing 15. The bore

2

afforded in bushing 15 may have any desirable diameter so that the bushing may be fitted over and surround a cable 16 as more fully hereinafter described.

5 The rear end of shell 10 has a shallow, annular groove 17 in its inside surface to receive a washer 18 of brass or other suitable metal disposed with its plane parallel to the plane of flange 14 of bushing 15. The circular hole afforded in washer 18 is coaxial with and considerably smaller in diameter than the bore in the bushing 15. A metallic substantially funnel-shaped or hollow cone-shaped member 19 is disposed so that its neck portion has a loose fit within the hole of the washer 18 when a cable is not attached thus leaving an annular space between the washer 18 and funnel 19 for a portion of the outer conductor of a cable to overlie the neck portion and underlie the washer as hereinafter described. The flaring 20 portion of funnel 19 opens forwardly into the shell 10.

A substantially cylindrically-shaped hollow sleeve 20 constructed of porcelain or any other suitable arc-resistant rigid insulating material is 25 disposed coaxially within the shell 10, with its inner end 21 located substantially midway of the length of cylindrical shell 10 and its outer or forward end (to the right in Fig. 1) slightly within the forward end of shell 10. The outside diameter of the sleeve 20 is somewhat less than the inside diameter of the shell 10, such that an annular recess or cavity 22 is formed between the inner wall 23 of shell 10 and the outer wall 24 of sleeve 20. The inner end portion 21 of sleeve 20 is enlarged to fit snugly and securely with the inner wall 23 of shell 10 or it may be flared to form a wedge-shaped space between wall 23 and the inner end 21 of sleeve 20 to permit a binding agent 25, such as cement, to be inserted in the wedge-shaped space for securing the sleeve 20 to the shell 10. If desired, a portion of the inner wall 23 and the outer surface of the enlarged or flared portion 21 may be notched or grooved as at 26 to improve the binding action of cement 25, or alternative means employed.

The inner wall 27 of sleeve 20 defines a bore of substantially uniform diameter along the major portion of its length. The inner end of the bore may be flared as at 28 to provide a funnel-shaped recess opening into the space 29 within the rear end of shell 10. A portion of the forward or outer end of the sleeve 20 may have a slightly larger internal diameter to receive a substantially cylindrical contact member 30 of brass or other suitable conducting metal. Contact member 30

may be provided with a flange 31 for abutting against a shoulder 32 on the inner wall 27 of the sleeve 20 to prevent inward movement of the contact 30. Cement or other sealing substance 33 desirably is inserted between contact member 30 and the adjacent portion of the inner wall 27. The outer surface of contact member 30 and the adjacent surrounding portion of inner wall 27 of sleeve 20 may be grooved or notched to improve the binding action of the cement 33, or alternative means employed.

Contact member 30 has a reduced neck portion or center contact 34 extending forwardly with its end substantially in the same plane with the forward end of sleeve 20, thus defining an annular recess 35 between the center contact 34 and the inner wall 27 of the sleeve 20. Contact member 30 is provided with an axial bore 36 throughout its length adapted to receive the inner conductor of a cable as herein described.

Inner wall 23 of shell 10 may be provided with a ring or annular flange 37 to abut the inner end 21 of the insulating sleeve 20 to secure sleeve 20 against inward movement. This is desirable in the assembly of the plug element so that the sleeve 20 is held in place before and during the application of the sealing material, such as cement 25. Flange or ring 37 may be integral with the shell 10 or desirably may be in the form of a washer secured to the shell in any suitable manner. Screws 38 may be threaded through the shell and washer for a purpose hereinafter described.

Upon the outer surface of shell 10 and substantially midway of its length is mounted an annular coupling 39 preferably having at its rear end an inwardly disposed flange portion 40. Coupling 39 is held against longitudinal movement towards the forward end of shell 10 by an annular flange 41 integral with shell 10 or secured thereto by any desirable means as shown. The forward end of coupling 39 is internally threaded at 42 for threaded connection to the socket element as hereinafter more fully described. Flange 41 may be externally threaded at 43 to permit coupling 39 to be secured over flange 41 to facilitate assembly and thus to hold coupling 39 against longitudinal movement in both directions.

The socket element is illustrated in Fig. 2 and compress a cylindrical shell 50 of metal, such as steel or brass, having a slightly larger internal diameter than the outer diameter of shell 10 of the plug element to permit shell 50 to be in snug sliding engagement over shell 10 when the plug and socket elements are being connected. The forward end (to the left in Fig. 2) of shell 50 is externally threaded at 51 to engage with the threaded portion 42 of coupling 39 of the plug element. The externally threaded portion 51 desirably may be on an annular flange or ring 52 integral with or secured to the rear end of shell 50 in any suitable manner, such as by welding, and may be provided with a lock ring 53 in threaded engagement therewith.

The forward end of shell 50 may also be provided with an annular groove for receiving a gasket or rubber washer adapted to seat against the flange 41 of the plug element.

The rear end (to the right in Fig. 2) of shell 50 has an external annular flange 54 integral with or suitably mounted on the outer surface of shell 50 and having a plurality of spaced holes 55 for receiving bolts or screws to permit secure mounting of the socket element onto ap-

paratus (not shown) to which connection is desired. Secured to the rear end of the shell 50 is an annular retaining member 56, a portion of which is bent inwardly to form a cylindrical ring 57 substantially parallel with the shell 50, thus defining an annular channel opening towards the forward end of shell 50, the free end portion forming a cylindrical ring 57.

A longitudinal insulating member generally indicated at 58 is disposed axially and with its major portion within the shell 50. Insulating member 58 has an enlarged cylindrical cup-shaped portion 59, a reduced central portion 60 and a neck portion 61 extending from said central portion. The central portion 60 is positioned substantially midway of the length of the member 58 and is of substantially circular cross section with an outside diameter somewhat less than the inner diameter of the ring 57 of retaining member 56, thus leaving an annular space between the ring 57 and the central portion 60. Portion 60 is secured to the inner surface of ring 57 by filling solder, cement or by other suitable means to make a tight connection. If desired, packing, such as asbestos, may be placed between portion 60 and ring 57 as at 60'.

The enlarged cup-shaped portion 59 of member 58 has a shoulder 62 engaging the inner end of ring 57 to aid in locating the member 58 within shell 50 and to improve the tightness of the connection between member 58 and shell 50. A cavity 63 of substantially circular cross section is defined by cylindrical rear sleeve portion 64 of the cup-shaped portion 59. The walls of sleeve portion 64 have such thickness that the sleeve 64 may fit into the annular recess 22 of the plug of Fig. 1. The neck portion 61 of the insulating member 58 extends rearwardly beyond the shell 50 and may be externally grooved or ribbed along its length to provide a longer insulating surface. A metallic contact member 65 is secured to the rear end of neck portion 61. Contact member 65 may be a disc or dish-shaped member disposed with its plane perpendicular to the axis of neck portion 61 with its wall spaced from and surrounding the end of neck portion 61. Contact member 65 may be secured to the end of the neck portion 61 by cement, solder or any other suitable securing means as indicated at 65'.

The insulating member 58 is axially bored throughout its length as indicated at 66, the rear end of the bore communicating with the cavity 63 within the cup-shaped, enlarged portion 59. A metallic electrically conducting connector rod 67 is positioned within and throughout the length of the bore 66, at its rear end being electrically in contact with the contact member 65 and at its forward end having a substantially cylindrical sleeve portion 68 extending into the cavity 63 a short distance. The cylindrical sleeve 68 is of such dimension that it is adapted to fit snugly over neck portion 34 of contact member 30 of the plug element, when the plug element and socket elements are telescoped together thus making a good electrical connection between neck 34 and cylindrical sleeve 68. If desired, sleeve 68 may be provided with a longitudinal slot or slots to improve resiliency and to facilitate the sliding of the sleeve 68 over the contact 30. The rear end of the rod 67 terminates in a lug or stud 69 projecting through the center of contact member 65, and secured thereto for connection with a transmission wire or for contact with brushes of a 78 rotating spark gap assembly, or any other elec-

trical contact element of apparatus to which the socket element may be attached. If desired, the stud 69 may be center-tapped or provided with a threaded recess 70.

In the structure described the several cylindrical members of the plug element and socket element are concentric relative to the longitudinal axes of the plug and socket elements. It will be noted that, when the plug element and socket element are connected, the respective axes will be co-linear, the cylindrical members of both elements thereby being concentric to the common axis. In this position the cup-shaped member 59 of the socket element will surround the cylindrical insulating member 20 of the plug element and it is preferably spaced therefrom to provide an air-gap, thus improving the insulating properties of the connection.

The plug and socket of the present invention as described above is particularly adapted for use with a coaxial type cable capable of conducting high voltages. Such a cable 16 as shown in Figs. 1 and 3 has usually, in sequence, a central conductor 11, a layer of insulating material 12, such as rubber or the like, a layer of copper braid sheathing 13 constituting an outer conductor of the cable, a layer of insulating cotton tape 14, a sheath or shield of steel braid armor 15 and an outer sheath 16 of natural or artificial rubber ("neoprene") or other suitable insulating material. It will be understood that Fig. 3 is an expanded view of a cable end to more clearly illustrate the construction thereof and the manner in which the indicated members of the plug element are applied to the cable end in the assembly but that this view should not be taken in the light of the following description as showing the exact dimensions or the relative lengths of each layer or of the exact positioning of the plug elements thereon. Also, it will be understood that while the description is directed to a cable of the above kind, the present invention may be used with any cable of similar construction having an inner conductor and an outer conductor or shield spaced therefrom by insulating material.

In attaching the plug element to a cable end, of the kind referred to, the clamping nut 12 and the cable bushing 15 are slipped over the end of the cable 16 for any desired distance. The outer sheath of insulating material 16 is removed for a short distance, for instance $2\frac{3}{4}$ " from the cable end. The layer of steel braid shielding 15 is then removed from the cable end to say within $\frac{1}{8}$ " from the end of the outer sheath 16 and the remaining portion is unwoven to the end of the outer sheath and the unwoven strands bent outwardly at right angles as indicated at 71 in Fig. 1. The cable bushing 15 is then moved into position against the bent strands which are trimmed off so that the protruding ends are slightly below the outer edge of the flange 14 of the bushing. If there is a layer of cotton tape, this is removed down to a point where the steel braid strands are bent. The metal washer 18 may then be moved over the copper braid 13 and down to a point where the outer sheath terminates, thereby positioning the outwardly protruding bent portions 71 of the steel strands between the washer 18 and the flange 14. If desired the surfaces of the washer 18 and the flange 14 engaging the bent strands may be serrated or notched to "bite" into the strands, when the plug is fully assembled, and provide a better frictional clamping action on the strands. The layer of copper braid 13 then is removed to within about $\frac{1}{8}$ " from the

washer 18 and the funnel 19 is slid over the inner layer of insulating material 12 so that its neck portion enters the hole of the washer 18 whereby its neck portion slides under the layer of copper braid spreading it outwardly over the neck portion and for a short distance over the flared portion of the funnel 19, as indicated at 72 in Fig. 1. The copper braid 13 is secured to the funnel member 19 and to the washer 18 by solder. The inner layer of insulating material 12 should be removed for a short distance from the end of the inner conductor 11 to expose the end portion of the inner conductor and, if desired, the insulating layer 12 may be tapered toward the end of the inner conductor. The cable end is then ready to be inserted into the rear end of the plug element 10. This may be done by inserting the exposed end of the cable into the cavity 29 so that the exposed end of the inner conductor 11 will fit into the bore 36 of the contact member 30. Upon engaging and tightening clamping nut 12 on the threaded portion 11 of shell 10, the cable end is forced tightly into position. If desired, washer 18 may be soldered or otherwise secured into the open rear end of shell 10. The tightening of the clamping nut 12 insures that the flange 14 of bushing 15 is clamped tightly against the outwardly bent strands 71 of the shielding to thus prevent the cable from turning or moving longitudinally with respect to the assembled plug element. Any excess of length of the center conductor which may protrude beyond the bore 36 of contact member 30 should be cut off and solder may be flowed into the bore to make a more secure connection. If desired, the center conductor and the end of the neck portion 34 may be filed or otherwise smoothed so that the end will be left rounded, thus permitting easier engagement with the socket sleeve 68.

With the plug element and cable end thus assembled, it will be noted that the plug element is substantially fluid tight. It may be found desirable, to insure better insulating qualities, to fill the inside of the shell 10 with a dielectric material which will also serve to eliminate any air space within the plug element. This may be accomplished by providing a closable aperture in the wall of the shell 10 through which dielectric material, such as wax, may be inserted. Preferably, however, one of the screws 38 in the annular ring 37 may be removed thus leaving an aperture for insertion of dielectric material after which the screw is replaced. Any suitable dielectric material, such as that sold under the trade names Dow-Corning Ignition Sealing Compound #4 or Anaconda Superseal #150, may be used depending upon the specific use to which the connector of the present invention is to be applied.

It will also be appreciated that the connector of the present invention is capable of being easily detachable. This may be accomplished by simply unscrewing coupling 39 of the plug element from threaded engagement with the threaded portion 51 of the socket element and then pulling the plug element away from the socket element. Similarly the plug and socket element may be easily and quickly connected by the reverse procedure.

Upon connecting the plug element with the socket element, it will be obvious from the above description that the outer shell 50 of the socket element, because of its slightly larger diameter, is adapted to overlap forward end of shell 10 of the plug element and to be secured thereto. As described herein the enlarged cup-shaped portion

58 of the insulating member 58 is of such dimension that it may be received in the annular recess between the outer shell 10 and the inner insulating member 20 of the plug element; and the socket sleeve 68 will override and be in good electrical contact with the neck portion 34 of contact member 30. It will be appreciated that in the assembled position of the plug and socket element, there is a continuous, good electrical connection between the inner conductor of the cable through the neck portion 34 of contact 30 with the socket sleeve portion 68 of the socket element through the metal tube 67 within the insulating member 58 to the contact member 65. Any current that may flow in the outer conductor of the cable is passed through the washer 18 to the outer shell 10 of the plug element and by the continuous metallic contact between the outer shell 10 of the plug element and the outer sleeve 50 of the socket element is passed to the flange 54 and thence to the apparatus to which the socket element may be attached, or vice versa. It will be understood, however, that the high voltages carried by the cable are usually passed through the inner conductor only, the outer conductor being used as a shield to prevent high voltage currents from passing out of the cable. It will be obvious that in passing high voltage pulses through the connector of the present invention, possibility of losses or flashing-over from the inner conductor to the outer conductor or to any surrounding medium is greatly reduced due to the telescoping relation of the insulating members, the space therebetween, and the increased distance between the inner and outer conductors.

A preferred form of the socket element has been described above for use as a terminal connection. It will be appreciated that a similar form of socket may be used for connection to a cable end so that the plug and socket elements may provide a detachable connector between two lengths of cable. This may be accomplished by providing suitable modifications of the socket element as will be readily understood by those skilled in the art in the light of the foregoing description.

What is claimed is:

1. A detachable connection for high voltage transmission coaxial type cable having in combination a plug element and a socket element separably engaged therewith, said plug element comprising an outer cylindrical metallic shell, one end of said shell being in threaded engagement with an annular clamping nut, a cylindrical cable receiving bushing held by said nut, a metallic washer on the shell positioned to surround a portion of the cable end and clamp outwardly bent portions of the cable sheathing between said bushing and said washer, a funnel-shaped member arranged to receive an inner insulator portion of the cable end and to engage within an end portion of an outer conductor of said cable in said washer whereby tightening of said clamping nut on said shell firmly secures said cable end to said shell and electrically connects the outer conductor to said outer shell, a substantially cylindrical sleeve of rigid insulating material fixed and spaced coaxially within the non-threaded end of said shell to provide an annular recess, and a metallic contact member rigidly mounted within and near the free end of said major portion of said sleeve, said contact member having a bore therethrough, one end of said bore communicating with the cavity defined by the inner walls of said shell and said insulating sleeve and connected with an exposed end of the center conductor of said cable, the 75

opposite end of said contact member having a reduced projecting neck portion.

2. A detachable connection as claimed in claim 1 wherein said socket element comprises a hollow cylindrical metallic sleeve having slidable fit with the outer shell of the plug element, the rear end of said metallic sleeve carrying an inwardly disposed retaining flange having a portion bent toward the opposite end of said metallic sleeve to define a cylindrical ring substantially concentric with said sleeve, a coaxial substantially cylindrical insulating member fixed in said ring having a hollow cup-shaped portion within and spaced from said sleeve and opening toward the forward end of said sleeve, said cup-shaped portion projecting into the recess between said outer shell and said insulating sleeve of said plug element, said insulating member having a neck portion extending rearward beyond the rear end of said sleeve and provided with an axial bore, a metallic contact member mounted on the extremity of said neck portion, a metallic electrical conductor disposed within said bore, the rear end of said conductor connected with said contact member, the forward end of said conductor extending into the recess within said cup-shaped portion and having a tubular shape and electrically engaged with the reduced neck portion of the contact member of said plug element and separable coupling means externally mounted on said sleeve and the shell of said plug element coupling said plug element to said socket element.

3. A socket element for a detachable connector for high voltage transmission coaxial type cable, comprising a hollow cylindrical metallic sleeve, an inwardly disposed retaining flange having a portion bent toward the forward end of said metallic sleeve to define a cylindrical ring substantially concentric with said metallic sleeve, a coaxial substantially cylindrical insulating member having a hollow cup-shaped portion within and spaced from said metallic sleeve and opening toward the forward end of said metallic sleeve, said insulating member having a central portion in substantially fluid-tight connection with said ring and a neck portion extending beyond said central portion and beyond the rear end of said metallic sleeve and provided with an axial bore, a metallic contact member mounted on the end of said neck portion, a metallic electrical conductor disposed within said bore, the rear end portion of said conductor connecting with said contact member, the forward end of said contact extending into the recess within said cup-shaped portion and having a tubular shape.

4. A connector member for terminating a coaxial cable, of the type which includes an inner conductor, a tubular dielectric encircling said inner conductor, a tubular outer conductor encircling said dielectric and a tubular sheath encircling said outer conductor, which connector member comprises a tubular shell of conducting material, a washer of conducting material abutting the rear end portion of said shell and having an inside diameter greater than the outside diameter of said outer conductor of said coaxial cable, a tubular bushing of greater internal diameter than the external diameter of said sheath and provided with an outwardly flanged portion disposed rearwardly of said washer and relatively movable to clamp between them an outturned end portion of said tubular sheath of said coaxial cable, means engaged and cooperating with said shell to urge said flanged portion toward said

washer so as to grip said end of said tubular sheath between said flanged portion and said washer, a tubular substantially funnel-shaped member provided with a rearwardly directed tubular neck extending through the said washer and spaced therefrom and receiving therearound the end of said outer conductor of said coaxial cable within said washer, a rigid dielectric sleeve secured to the interior of said metallic shell, and a contact member secured to the interior of said sleeve and provided with a bore having the end of said inner conductor of the said coaxial cable engaged therein, all of the elements of said coaxial cable and of said connector member being substantially coaxial.
